UNITED STATES PATENT OFFICE

168,581

FOLDING BEDFRAME

William K. McInerney and James M. McInerney,
Grand Rapids, Mich.

Application March 13, 1952, Serial No. 18,866

Term of patent 14 years

(Cl. D5—4)

To all whom it may concern:

Be it known that we, William K. McInerney and James M. McInerney, citizens of the United States, residing at Grand Rapids, in the county of Kent and State of Michigan, have invented a new, original, and ornamental Design for Folding Bed Frame, of which the following is a specification, reference being had to the accompanying drawing, forming part thereof.

Fig. 1 is a perspective view of a folding bed frame in open position showing our new design.

Fig. 2 is a side elevation of the same, and

Fig. 3 is a perspective view of the same in folded position.

We claim:

The ornamental design for a folding bedframe as shown.

WILLIAM K. McINERNEY.
JAMES M. McINERNEY.
